UNITED STATES PATENT OFFICE

157,185

COMBINATION SPOON, FORK, AND HOLDER

Eoina Nudelman, Chicago, Ill.

Application February 17, 1948, Serial No. 144,556

Term of patent 14 years

(Cl. D44—29)

To all whom it may concern:

Be it known that I, Eoina Nudelman, a citizen of the Republic of France, residing at Chicago, State of Illinois, have invented a new, original, and ornamental Design for a Combination Spoon, Fork, and Holder, of which the following is a specification, reference being had to the accompanying drawing, forming a part thereof.

In the drawings:

Fig. 1 is a front view of a combination spoon, fork, and holder showing my new design.

Fig. 2 is a rear view, and

Fig. 3 is a side view.

I claim:

The ornamental design for a combination spoon, fork, and holder, as shown,

EOINA NUDLEMAN.
